The ornamental design for a four-finger glove, as shown and described.

DESCRIPTION

FIG. 1 is a front elevational view showing a four-finger glove secured about a left hand of a user;

FIG. 2 is a back elevational view showing the four-finger glove secured about the left hand of the user;

FIG. 3 is a left side perspective view thereof;

FIG. 4 is right side perspective view thereof;

FIG. 5 is a top plan view thereof;

FIG. 6 is a bottom plan view thereof;

FIG. 7 is a front elevational view showing another embodiment of a four-finger glove secured about a right hand of a user;

FIG. 8 is a back elevational view showing the four-finger glove secured about the right hand of the user;

FIG. 9 is a right side perspective view thereof;

FIG. 10 is left side perspective view thereof;

FIG. 11 is a top plan view thereof; and,

FIG. 12 is a bottom plan view thereof.

The hand shown in broken lines illustrates the environment in which the four-finger glove is worn, and forms no part of the claimed design. The broken lines shown on the four-finger glove itself are stitching shown for illustrative purposes, and form no part of the claimed design.
